WALL CONSTRUCTION

John J. Olsen, San Francisco, Calif.

Application June 11, 1937, Serial No. 147,716

11 Claims. (Cl. 72—44)

The present invention relates to wall construction, and more particularly to improvements in a wall construction in which two parallel walls composed of blocks laid in corresponding courses are bound together by reinforcing tie means imbedded in spaced columns of concrete poured between the walls formed by the blocks.

An object of the invention is to provide a wall construction which is practical, economical to construct and which possesses advantages not provided in prior art structures of this character.

Another object of the invention is to provide a novel form of reinforcing tie means which can be assembled as the spaced wall forming blocks are laid one course upon the other.

Another object of the invention is to provide a novel arrangement of tie means embodying relatively long elements which can be assembled in a simple and convenient manner without threading the interlocking parts over the longer elements.

A further object of the invention is to provide a new and novel form of concrete retaining means between walls formed by the parallel courses of blocks which will permit the pouring of concrete in spaced columns between the retaining walls.

Other objects and advantages of the invention will be in part pointed out and in part evident to those skilled in the art to which the invention appertains.

For a better understanding of the invention reference should be had to the accompanying drawing, wherein there is shown by way of illustration and not of limitation preferred embodiments thereof.

In the drawing:

Figure 1 is a fragmentary sectional view of a wall constructed in accordance with the invention with the reinforcing tie means assembled in its operative position.

Figure 2 is an enlarged exploded fragmentary view in perspective, showing the details and the manner of assembling the reinforcing elements illustrated in Figure 1 of the drawing.

Figure 3 is a view similar to Figure 1, showing a modified form of the present invention.

Figure 4 is an enlarged perspective view showing the manner in which the reinforcing elements of the wall shown in Figure 3 are assembled.

Figure 5 is a fragmentary perspective view showing a detail of the reinforcing means contemplated by this invention, and

Figure 6 is a fragmentary sectional view taken along line VI—VI of Figure 1, looking in direction of arrows, showing the concrete column

forming and retaining means contemplated by the invention.

As illustrated in Figure 1 of the drawing, one embodiment of the wall construction contemplated by this invention comprises a pair of spaced walls 10 and 11 composed of similar slabs or blocks 12 laid in parallel courses with the vertical joints of one course disposed at an intermediate point with respect to the vertical joints of the corresponding course in the other wall, the blocks or slabs 12 preferably having tongues 13 along their upper edge, and grooves 14 along the lower edge, so that when the blocks are assembled, the tongues 13 and the grooves 14 on the adjacent blocks will interlock. Extending between the walls 10 and 11, the invention contemplates a novel arrangement of interlocking elements which serve to hold the parallel courses of blocks 12 in spaced relation and reinforce the wall in its vertical plane when completed. In one form this reinforcing means, as is more clearly illustrated in Figure 2 of the drawing, comprises a transversely disposed tie member 15 having an upset end 16 that is adapted to cooperate with a tongue 13 and groove 14 of two blocks 12 in one of the walls, and a second tie member 17 having a similarly upset end 18 which cooperates with a tongue 13 and groove 14 on blocks 12 of the opposite wall. This second tie member 17 has a downwardly depending diagonal portion 19 that is adapted to engage with another tie member 15 associated with the next lower course of blocks 12 in one of the walls 10 or 11. Associated with the members 15 and 17, the reinforcing means also contemplates the use of vertically extending flat bars 20 and 21 which pass through L-shaped slots 22 and 23 formed in the tie member 15 and a similar slot 24 in the tie member 17. At the lower end of the downwardly depending diagonal portion 19 of the tie member 17 there is a tongue 25 that is adapted to project through the slots 22 and 24 in the tie members 15 and 17, and adjacent the tongue 25 there are two horizontally disposed bearing forming feet 26 which rest upon the upper surface of the tie member 15 when the parts are assembled, as illustrated in Figure 1 of the drawing. With this arrangement it will be seen that the tie forming members 15 and 17 will be secured together against endwise displacement by the vertically extending rod 20, and that with the downwardly depending diagonal portions 19 arranged at oppositely disposed angles, as shown, the two walls 10 and 11 will be reinforced in their vertical plane. The disposition of the diagonal 55

portions 19 of the tie members 17 at oppositely disposed angles between the successive courses of blocks 12 in the wall construction is made possible by merely reversing the positions of the 5 tie members 15 and 17 as each course of blocks is added to the wall construction.

In Figure 3 of the drawing, instead of resorting to tie members 15 and 17, the object of the invention is obtained by substituting for these 10 members a preformed channel-like strut or beam 27 having right angled flanges 28 at the edges thereof. The beam or strut member 27, as here shown, is lightened in weight by cutting out triangular sections thereof, which leave diagonal 15 struts 29 between the flanged edges thereof. When the beam or strut member 27 is used, it will preferably have a length substantially equal to the height of the wall, but it is to be understood that a number of these elements 27 may 20 be placed end to end, or in end overlapping relation in a vertical line as the courses of blocks 12 forming the walls 10 and 11 are built up. As a means for tying the blocks 12 to this latter form of reinforcing means, the invention contemplates 25 a transversely extending tie forming member 30 having upset ends 31 and 32 which respectively interlock with the tongues and grooves upon the blocks 12 of the walls 10 and 11.

As shown in Figure 4 of the drawing, the tie 30 forming member 30 is provided with oppositely disposed L-shaped slots 33 and 34 which are adapted to engage the outer edges of the beam 27 and the right angled flanges 28. The slots 33 and 34, like the slots 22, 23 and 24 of the 35 earlier described embodiment, are of L-shape, and the portions of the tie member 30 included in this L configuration, designated by the numeral 35, are adapted to be bent or deformed so as to permit a sidewise engagement between the tie member 17 and the vertical portions and flanges of 40 the struts 27.

In Figure 5 of the drawing, there is shown a portion of the tie member 30 with the portion 45 35 of this L-shaped slot 34 deformed to permit the insertion of the beam 27 with its flange 28 therein. In connection with this figure of the drawing, it may be pointed out that this illustration also shows the manner in which the slots 22 and 23 of the tie member 15 and the slot 24 50 of tie member 17 may be deformed to facilitate assembly of the parts.

Before passing on to a description of the remaining features of this invention, attention is again directed to Figures 1 and 3 of the drawing, and particularly to the showing of inverted metal 55 channel-like members 36 in conjunction with the tongues 13 and the grooves 14 upon the blocks or slabs 12. These inverted metal channel-like members 36 are preferably of considerable length, and when laid over a course of blocks 12 serve as an additional reinforcing means in that they function to prevent an endwise separation between the ends of the successive blocks 12 in any one course. It is to be understood, however, that the use of these inverted metal channel-like members 36 is not essential to a full utilization of the invention as hereinbefore described. As an additional feature of the invention, to facilitate an assembly of the blocks 12 60 in the parallel courses of the walls 10 and 11 with the reinforcing means illustrated in Figures 3 and 4 of the drawing, the blocks 12 may each be provided with imbedded and projecting deformable metal tabs 37 intermediate their top and 65 bottom edges. When these tabs 37 are provided 70

upon blocks 12, they form a means for positioning and securing the blocks in proper spaced relation, while the transversely extending tie forming members 30 are being assembled in interlocking relation with the vertical beam or 5 strut 27. While reference is here made to this feature, it is to be understood that it does not constitute a necessary part of the invention, as the wall forming blocks 12 can also be properly assembled without resort to this additional securing means.

As illustrated in Figure 6 of the drawing, the invention, in addition to the reinforcing and tying means between the walls 10 and 11 formed by the blocks 12, also contemplates an incase- 15 ment of the tie means at spaced points along the wall, and to facilitate a pouring of the concrete about these reinforcing and tying elements without entirely filling the space between the walls 10 and 11, the blocks 12 are each provided 20 at spaced points along their inside top edge with notches 38 into which transversely extending supporting rods 39 may be disposed at each side of the reinforcing and tie forming members when assembled as above described. As shown in this 25 figure of the drawing, the transversely extending supporting rods 39 support a metallic curtain or transverse partition forming member 40 which has a turned over edge 41 along its top edge that is adapted to hook over one of the supporting 30 rods 39. The metallic transverse partition forming members 40 have a vertical dimension slightly greater than the height of the blocks or slabs 12, and when assembled, their lower ends 35 are adapted to project downwardly inside of the next lower transverse partition forming member 40. When these partition forming members 40 are arranged in this manner they form two opposed transverse walls between the blocks 12 of the walls 10 and 11 between which concrete may 40 be poured to incase the reinforcing and tie forming 45 elements assembled into the wall construction as previously pointed out. When the transverse partition forming members 40 are constructed of metal and are suspended in the manner illustrated and described, it will be readily seen that, if desired, they may be individually withdrawn from the wall after the concrete 50 poured therebetween has hardened. Consequently, these partition forming members 40 and their supporting rods 39 may be used over and over as the concrete column thus formed increased in height and/or in connection with additional similar columns at other points in the wall construction.

While I have, for the sake of clearness and in order to disclose the invention so that the same can be readily understood, described and illustrated specific devices and arrangements, I desire to have it understood that this invention is not 55 limited to the specific means disclosed, but may be embodied in other ways that will suggest themselves to persons skilled in the art. It is believed that this invention is new and it is desired to claim it so that all such changes as come 60 within the scope of the appended claims are to be considered as part of this invention.

Having thus described my invention, what I claim and desire to secure by Letters Patent is—

1. In a wall construction, the combination of 70 two surface forming walls disposed in spaced relation and composed of blocks laid in corresponding courses and having cooperating tongue and groove surfaces along their top and bottom edges, transversely extending tie forming means cooper- 75

ating with the tongue and groove of said blocks for retaining said blocks in spaced relation, and diagonally extending truss forming means between said walls interlocking with said tie forming means, and a reinforcing means disposed in spaced relation with each course of blocks and extending throughout the height of the walls and interlocking with the ends of said transversely extending tie forming means for reinforcing said walls in their vertical plane.

2. In a wall construction, the combination of two surface forming walls disposed in spaced relation and composed of blocks laid in corresponding courses and having cooperating tongue and groove surfaces along their top and bottom edges, transversely extending tie forming members for each course of blocks cooperating with the tongue and groove of said blocks and disposed in a vertical line between said walls for retaining said blocks in spaced relation, vertically extending truss forming means between said walls interlocking with said tie forming members for reinforcing said walls in their vertical plane, and means at each side of the vertical line of tie forming members forming retaining partitions transverse to the plane of the walls between which concrete may be poured about said tie forming members and said vertically extending truss forming means to complete the wall construction.

3. In a wall construction, the combination of two parallel surface forming walls composed of blocks laid in corresponding courses with the vertical joints of one course disposed at an intermediate point with respect to the vertical joints of the corresponding course in the other wall, a plurality of reinforcing tie forming members extending between said walls and interlocking with the joints between each course of blocks, said tie forming members being arranged in a vertical line one above the other between the walls, curtain supporting rods extending between said walls supported at the upper edge of each course of blocks and disposed one at each side of said reinforcing tie forming members, and a series of curtains hung in overlapping relation between the curtain rods of each course of blocks forming a cavity into which concrete may be poured to surround said tie forming members as the courses of blocks are assembled.

4. In a wall construction, the combination of two parallel surface forming walls composed of blocks laid in corresponding courses with the vertical joints of one course disposed at an intermediate point with respect to the vertical joints of the corresponding course in the other wall, reinforcing tie forming members extending between said walls and interlocking with the joints between each horizontal course of blocks, said tie forming members being arranged at spaced points along the wall in vertical relation one above the other, supporting rods extending between the upper edges of each course of blocks at each side of said reinforcing tie forming members, and a series of metal plates suspended vertically in overlapping relation between said supporting rods and at each side of the tie forming members between which concrete may be poured to encase said reinforcing tie forming members as the courses of blocks are assembled.

5. In a wall construction, the combination of two surface forming walls disposed in parallel relation and composed of blocks laid in corresponding courses with the vertical joints of one course disposed at an intermediate point with respect to

the vertical joints of the corresponding course in the other wall, said blocks having cooperating tongue and groove forming surfaces along their top and bottom edges, a plurality of tie forming members arranged in a vertical line and engaging said tongue and groove surfaces at its ends for holding each course of blocks in spaced relation, vertically extending reinforcing means connected between said tie forming means, said blocks each having notches along their inside top edges for the reception of a transversely disposed supporting rod, supporting rods engaging opposite notches at each side of said tie forming means and said vertically extending reinforcing means, and a transverse partition forming member suspended from each of said supporting rods and disposed inside of the next lower supporting rod with respect to said tie forming members forming a retaining means for wet concrete when poured around said tie forming members and reinforcing means.

6. In a wall construction, the combination of two surface forming walls disposed in parallel relation and composed of blocks laid in corresponding courses with the vertical joints of one course disposed at an intermediate point with respect to the vertical joints of the corresponding course in the other wall, said blocks having cooperating surfaces along their top and bottom edges, a plurality of tie forming members arranged in a vertical line and secured between said surfaces at its ends for holding said walls in spaced relation to each other, means forming a vertically extending reinforcing connection between said tie forming means, said blocks each having notches along their inside upper edges for the reception of a transversely disposed rod, a rod extending between each course of blocks engaging opposite notches at each side of said tie forming means and said vertically extending reinforcing connection, and a partition forming member suspended from each of said rods and hanging inside of the next lower rod with respect to said tie forming members forming a transverse retaining partition at each side of said tie forming means between which wet concrete may be poured to encase said tie forming members and reinforcing means.

7. A reinforcing and tie forming means for walls of the type having spaced and preformed blocks built up in spaced parallel courses, comprising a tie forming member having block engaging ends adapted to extend horizontally between the parallel courses of blocks, a diagonally extending strut portion connected to a second similar tie forming member arranged vertically in alignment therewith, and a vertically extending tie bar disposed in spaced relation with each course of blocks and interlocking with said tie forming members adjacent their ends.

8. A reinforcing and tie forming means for walls of the type having spaced and preformed blocks built up in spaced parallel courses, comprising a tie forming member having a block engaging end adapted to extend into the space between the parallel courses of blocks, a second tie forming member having a block engaging end adapted to extend into cooperating relation with said first tie forming member and diagonally to a second similar tie forming member, and a vertically disposed continuous rod adapted to interlock a plurality of said tie forming members in spacing and truss forming relation between the parallel courses of the wall forming blocks.

9. In a reinforcing tie bar for spacing and re-

inforcing walls constructed of spaced courses of preformed blocks, comprising a flat strip of metal having L-shaped slots cut into one edge thereof into which a vertically disposed tie rod may be inserted by deforming the portion of said tie bar included in the L configuration of said slot, whereby the vertically disposed tie bar may be inserted sidewise into said slot and retained therein by reforming the portion of said tie bar included in the L configuration of said slot to its original position.

10. In a wall construction of the character described having two parallel surface forming walls of preformed blocks laid in corresponding courses with the vertical joints of one course disposed at an intermediate point with respect to the vertical joints of the corresponding course in the other wall, the combination of reinforcing metallic tie members extending between each course of blocks and arranged in vertical relation to each other, a rod at each side of said reinforcing means supported at the top of each course of blocks and

extending transversely between the walls formed by said blocks, and a metal plate suspended upon each of said rods and extending inside of a lower similarly suspended metal plate, and a column of concrete encasing said reinforcing means and held in position by said metal plates.

11. In a wall construction, the combination of two parallel surface forming walls of preformed blocks laid in corresponding courses with the vertical joints of one course disposed at an intermediate point with respect to the vertical joints of the corresponding course in the other wall, reinforcing metallic tie members extending between said walls and arranged in vertically spaced relation, and a removable metal plate suspended from the top of each course of blocks at each side of said reinforcing tie members and extending downwardly inside of a similarly suspended metal plate, said metal plates forming transversely extending partitions between which concrete is poured to encase said reinforcing means.

JOHN J. OLSEN.
